UNITED STATES PATENT OFFICE.

CHARLES B. SALA, OF MINERVA, OHIO.

SPEED-INDICATOR.

1,116,848.

Specification of Letters Patent. Patented Nov. 10, 1914.

Application filed September 17, 1912. Serial No. 720,746.

To all whom it may concern:

Be it known that I, CHARLES B. SALA, citizen of the United States, residing at Minerva, in the county of Stark and State of Ohio, have invented certain new and useful Improvements in Speed-Indicators, of which the following is a specification.

This invention relates to speed indicators and controlling devices particularly adapted for use in connection with automobiles, although capable of application to any rotating part or shaft and to the engine which drives the same.

As applied to a motor vehicle the object of the invention is to provide an improved indicator which will show in such manner as to indicate by sight and sound the speed at which the vehicle is traveling, and if desired to control the operation of the engine so that it will be stopped when it exceeds a certain speed. Obviously it may be applied to a stationary engine, to indicate and control the operation thereof.

The indicator includes a visible device, and also a bell, either of which may be operated by suitable mechanism at a predetermined speed.

In the accompanying drawings—Figure 1 is a side elevation of the indicator, partly in section. Fig. 2 is a side elevation showing the exterior of the casing.

Referring specifically to the drawings, 12 indicates a casing which may conveniently be made of metal and it is formed or provided at the top with a bell 7 adapted to be struck by the hammer 7^a of an ordinary electric bell operating device mounted within the casing and indicated at 7^b. On the outside the casing is marked with a scale 40 of figures indicated at 6, for the purpose of indicating speed in miles, or otherwise. An arrow 8 cooperates with this scale, and this arrow is mounted on a pin 8^a which extends through a slot 15 in the casing and is attached to the upper end of a lazy tong structure, the members of which are indicated at 9 and which are arranged for vertical movement within the casing. The lower levers of the lazy tongs are provided at their 50 lower ends with blocks 10 which slide in guides 11 at the sides of the casing, and serve to hold the lazy tongs in upright position. A pin 29 is connected to the lower pivot of the lazy tongs and stands vertically thereunder, resting at its lower end on the upper end of a vertical shaft X which is

driven in any suitable manner, as by a belt X', permitting vertical movement or shift of the shaft. The lower end of the shaft is reduced and rests in a bearing in a plate 60 or support Y.

A centrifugal governor mechanism having weights W is mounted on the shaft and is driven thereby, the lower collar 40 of the governor being fast on the shaft and the upper collar 41 loose thereon and the latter is provided with a neck having a shoulder 42 which is carried in a bearing in a cross piece 30 which is fixed to the casing and through which the shaft X extends, so that 70 the upper collar is supported in a relatively stationary position, the shaft X being movable up and down through the upper collar and the cross piece as the weights operate centrifugally. A spring S normally retracts the weights and lowers the shaft to the extent permitted by the lower bearing.

One terminal 14 of the bell device is arranged to be struck by an arm 13 projecting from the lazy tongs, said arm being in 80 the bell circuit, and when the lazy tongs are lifted or extended sufficiently to close the circuit the bell is operated to sound an alarm which continues to ring as long as the circuit is closed. I also provide an arm 85 18 carried by a set screw 17 working in a slot 16 in the casing, and connected to one of the wires 18 leading from the ignition mechanism of the engine, not shown. At 90 a predetermined point or speed, the arm 13 strikes the terminal 18 and grounds the circuit to the ignition mechanism thereby stopping the engine. By means of the set screw 17 the contact member 18 may be raised or lowered to desired position in 95 order to limit the operation of the engine to any desired speed.

When the shaft X is driven the weights W fly out in consequence of centrifugal force and lift said shaft which by means 100 of the connecting rod 29 lifts or extends the lazy tongs thereby raising the pointer 8 which indicates the speed, and in due time acting to sound the bell and ground the igniter circuit by the means above described. 105 When the vehicle or engine is stopped the spring S and the weight of the parts causes the shaft X to drop with obvious results.

When used on an automobile the casing will be mounted in such position thereon 110 that the indicator will be visible from the street, or externally, and the devices will

- preferably be made of such size that the speed indicator can be seen from a distance, whereby violations of speed laws can be observed, and will also be indicated by the sounding of the bell, and when the stop devices are used the engine will also be stopped when the speed exceeds a certain limit. The device can be used in connection with stationary engines for indicating the speed of rotation of the main shaft, or other parts, suitable transmission being provided in one instance to the automobile wheels and in the other instance to some rotating part of the engine.
- 10 15 The use of the invention is not limited to any particular purpose, nor is the construction limited to the particular mechanism illustrated and described.
- What I claim as new is:
- 20 1. A speed indicator comprising an upright shaft shiftable lengthwise, a centrifugal device mounted on and driven by said shaft and operatively connected thereto

to shift the shaft according to the speed, a lazy tong structure the lower end of which 25 rests on the upper end of said shaft, and a pointer mounted on the upper end of said lazy-tong structure and operated thereby to indicate speed.

2. A speed indicator comprising a casing 30 having guides therein, lazy tongs located in the casing and provided with blocks slideable in said guides, an indicating device actuated by the lazy tongs, a shaft projecting into the casing and operatively 35 connected to the lazy tongs, and centrifugally operated means to shift the shaft lengthwise and extend the lazy tongs, according to the speed of rotation of the shaft.

In testimony whereof, I do affix my signature in presence of two witnesses.

CHARLES B. SALA.
